SPRAY GUN ADAPTER

Filed Oct. 28, 1935

UNITED STATES PATENT OFFICE

2,051,518

SPRAY GUN ADAPTER

James L. Cunningham, Chicago, Ill., assignor to
Sherwin-Williams Co., Cleveland, Ohio, a cor-
poration of Ohio

Application October 28, 1935, Serial No. 46,981

4 Claims. (Cl. 299—88)

Spray guns are in common use in automobile repair shops and various other places for spraying paints, lacquers, and other materials upon the surfaces to be finished or refinished. In repair shops particularly, a large number of colors are required to be kept in stock and when any particular color is needed a quantity of the material is poured from the can in which it comes from the factory into the receptacle of the spray gun. The gun is then attached to the receptacle and the material is sprayed as desired. When that particular job is finished, the material remaining in the receptacle is poured back into the can and the receptacle is required to be cleaned out before another color can be used. All of this results in a considerable loss in both time and spraying material.

The purpose of my present invention is to obviate these losses by providing an adapter by means of which a spray gun may be attached directly to the can or container in which the material to be sprayed is received. When any particular color is required the top of the can is simply removed, the adapter is applied to the can, and the spray gun is then attached to the adapter, whereupon the material may be sprayed directly from the can. When the job is finished, the gun and adapter are removed and the can is covered and set away without loss of material or time required for cleaning. By reason of this adapter one spray gun may be used repeatedly with any number of cans of material with a considerable saving in material and also in time for the user.

To facilitate an understanding of my invention, I have illustrated on the accompanying drawing preferred embodiments thereof from an inspection of which, in connection with the following description, many of the inherent advantages of my invention should be understood and appreciated.

40 Referring to the drawing,

Fig. 1 is a side elevation exemplifying my adapter applied to a container and a spray gun attached thereto;

45 Fig. 2 is a sectional view on the line 2—2 of Fig. 1;

Fig. 3 is a fragmentary sectional view on the line 3—3 of Fig. 1;

Fig. 4 is a fragmentary side elevation showing one of the adapter locking devices;

50 Fig. 5 is a plan view of a modified form of my invention; and

Fig. 6 is a sectional view on the line 6—6 of Fig. 5.

55 Referring first to Figs. 1 to 4, inclusive, ref-

erence character 1 indicates a container of the pouring type, such as is disclosed in United States Patent No. 1,997,291 and which includes an upwardly extending pouring throat 8 shaped as illustrated in Fig. 3.

5 My adapter for this type of container comprises a member 9 of substantially cylindrical shape provided on its lower face with an upwardly extending groove 11 adapted to receive the upwardly extending neck of the can, the inner wall of the 10 groove being proportioned to snugly fit within the throat of the neck so as to practically preclude leakage therebetween. If preferred, a gasket 12 may be positioned in the groove to engage the upper perimeter of the can neck to insure against 15 leakage. Suitable means are provided for locking or otherwise attaching the adapter member to the container and for illustrative purposes I have shown such means as comprising a plurality of cam levers 13 fulcrumed at 14 between laterally extending ears 15 so that when the levers are swung into the position shown in Figs. 1, 4, and 5 their cam portions will be engaged beneath the rim of the container neck so as to lock the adapter member securely to the container. 20

25 The adapter is also provided with laterally extending lugs or pintles 16 adapted for detachable connection with the attaching arms 17 of a spray gun indicated generally by reference character 18, the structural details of which are im- 30 material as regards the present invention. The ends of the arms 17 are provided with eyes preferably open at one side for ready engagement with lugs 16, as will be apparent from Fig. 1.

35 The gun includes a tube 19 adapted to project downwardly into the container, as shown, and upon this tube is mounted a top or cap member 21 which ordinarily fits over and closes the top of the spray gun receptacle and, in this instance, correspondingly fits the top of the adapter member 9. A gasket 22 is employed to insure against leakage at this point. The top 21 is secured to the tube 19 between lock nuts 23 and 24 and the hub 25 connecting the arms 17 is interiorly threaded for connection with a correspondingly 40 threaded sleeve 26 surrounding the tube 19 and provided with a handle 27. It will be apparent that by threading the sleeve 26 downwardly on the hub 25 a downward pressure will be exerted upon the cap 21 and an upward pressure on the 45 arms 17, to thereby clamp the cover member snugly against the top of the adapter and securely attach the gun to the adapter.

50 In using my invention, after the cover has been removed from the can containing the desired 55

spraying material the adapter member 9 is inserted into position upon the container and is securely locked thereto by the cam levers 13. The spray gun is then attached by connecting the terminal eyes of the arms 17 over the stud 16, whereupon the sleeve 26 is screwed down to securely clamp the parts in assembled relation. The apparatus is now ready for use and the material may be sprayed directly from the container in which it is received and without the necessity of pouring it into a spray gun receptacle. When the job is finished the gun is removed by loosening up the sleeve 26, whereupon the cam levers are swung outwardly to release the adapter so that it may be removed from the container. In many instances it is unnecessary to disconnect the gun from the adapter, as the gun and adapter may be removed as a unit from the container by simply releasing the locking levers.

20 The form of the invention shown in Figs. 5 and 6 is the same in principle as that previously described but is designed for use in connection with a different type of can, designated generally by reference character 28, and which has a pouring mouth 29 located below the upper end of the can proper instead of above, as in the type previously described. In this instance the adapter member 31 is provided with a groove 32 adapted to receive the rim of the can, the inner wall 33 of the groove being designed to fit within the annular depression surrounding the pouring mouth of the can. The locking levers 13 in this instance engage beneath the bead of the can to lock the adapter member in position. The gun is attached to the adapter member in the manner previously explained.

It will be apparent from the foregoing that my invention enables a spray gun to be used directly in connection with the container in which the spraying material is received, and obviously the necessity of pouring the material out into another receptacle and also the necessity of cleaning such a receptacle after each use is eliminated. Considerable economy, both in time and material, is thereby effected and the spraying material is at all times retained in its original container without danger of spilling or of contamination by dust and dirt.

The details of my invention illustrated and described are obviously capable of considerable variation within the scope of the invention as defined in the following claims:

I claim:

1. The combination with a container for coating materials having a restricted cylindrical throat terminating in an outwardly flared pour-

ing mouth, of a member provided with a downwardly opening annular groove adapted to receive the flared mouth of the container, the inner wall of said groove being shaped to enter and fit said throat and the outer wall thereof being adapted to surround said flared mouth, inwardly projecting means carried by said outer wall of the member and movable laterally of said container for engaging beneath the rim of said mouth to secure said member to said container, a closure engageable with the top of said member to close said container, and means carried by said member cooperable with companion means carried by a spray gun whereby said gun may be attached to said member.

2. The combination with a container for coating materials having a restricted cylindrical throat terminating in an outwardly flared pouring mouth, of a member provided with a downwardly opening annular groove adapted to receive the flared mouth of the container, the inner wall of said groove being shaped to enter and fit said throat and the outer wall thereof being adapted to surround said flared mouth, means pivotally mounted on and carried by said outer wall of the member for engaging beneath the rim of said mouth to secure said member to said container, and means carried by said member and cooperable with companion means carried by a spray gun whereby said gun may be attached to said member.

3. The combination with a container for coating materials having a restricted cylindrical throat terminating in an outwardly flared pouring mouth, of a member shaped to receive the flared mouth of the container and comprising a depending flange surrounding said mouth, inwardly projecting means carried by said flange and movable laterally of said container for engaging beneath the rim of said mouth to secure said member to said container, and cooperating means carried by said member and a spray gun, respectively, whereby said gun and member may be secured together.

4. The combination with a container for coating materials having a pouring mouth, of a member shaped to receive the mouth of the container and comprising a depending flange surrounding said mouth, means movable laterally of said mouth for engaging said flange beneath said mouth to secure said member to said container, and cooperating means carried by said member and a spray gun, respectively, whereby said gun and member may be secured together.

55. JAMES L. CUNNINGHAM.
